FRED W. KAMIN
ATTORNEY

UNITED STATES PATENT OFFICE

HAROLD W. LANGBEIN, OF LOS ANGELES, CALIFORNIA

ARBOR

Application filed November 5, 1928. Serial No. 317,295.

My invention relates to arbors and the like for supporting a part to be worked on, and it consists of a self-centralizing arbor in which the device to be supported will be concentrically supported by the arbor, when the device is attached to the arbor.

One of the important uses of my invention is for supporting automobile wheels for truing the brake-drums thereof. This is ordinarily accomplished on a drum-lathe which includes an arbor which supports the wheel. The arbor is usually carried by a spindle which is driven by a suitable motor. The wheel is concentrically secured on the arbor, and is rotated. The drum-lathe is provided with a carriage which supports a cutting tool, which cutting tool is adapted to work on the surface of the brake-drum, and to make it concentric with the center of rotation of the wheel.

The openings in the hubs of the different wheels are of different sizes and tapers, and in the ordinary form of drum-lathe it is necessary to have a number of different arbors or a number of different sleeves so that these different wheels may be accommodated.

One of the objects of this invention is the provision of an arbor which is susceptible of supporting various devices having different sizes of openings, or openings with different tapers.

A further object of the invention is the provision of an arbor having a pair of centralizing-members which are readily adjusted relative to the device to be supported, so that the device will be concentrically supported. The centralizing-means are designed so that they may be made to concentrically support devices having different sizes and tapers or openings.

A further object of the invention resides in the provision of a self-centering arbor which includes a primary centralizing device and a secondary centralizing device. The primary-means is provided for moving the device into engagement with the primary centralizing-member and the secondary-means is provided for moving the secondary centralizing-member into engagement with the device.

A further object of the invention is to provide a self-centering arbor in which the primary centralizing-member is adapted to rest in the opening of the device, and in which the secondary centralizing-member engages the device at one end of the central opening thereof.

A further object of the invention is to provide a self-centering arbor in which one of the centralizing-members is provided with a frusto-conical face adapted to engage the device at one end of the central opening thereof.

It is a still further object of the invention to provide a device of the character mentioned in which the primary and secondary means are provided in the form of nuts threadedly advanced on the arbor.

The arbor of the invention is adapted to be carried by a spindle. The spindle has an opening formed through it, one end of which is tapered, and the arbor has a tapered end fitting into the tapered part of the spindle.

It is an object of this invention to provide a means for separating the arbor and the spindle, which consists of a nut or equivalent part screwed on to the arbor, and adapted for advancement toward the spindle so that the end of the spindle may be engaged and the arbor thus forced from the spindle.

A further object of the invention resides in the provision of an arbor and spindle combination as specified above, in which the two parts are screwed together by means of a bolt extending through the end of the spindle and threadedly engaging the arbor, the bolt also engaging one end of the spindle, thus holding said arbor to said spindle.

Other objects will be pointed out in the following description.

The invention may be best understood by reference to the accompanying drawings, in which

Fig. 1 is a fragmentary view partly sectioned, showing the invention applied to a drum-lathe.

Fig. 2 is an enlarged sectional view of the self-centering arbor of the invention.

Figs. 3 and 4 are sections taken on the lines 3-3 and 4-4 of Fig. 2.

Referring to the drawing in detail, the numeral 11 represents a supporting structure which includes bearings 12 and 13 which support a rotatable spindle 14. The spindle 14 has a worm gear 15 secured to it, which worm gear is adapted to be rotated by a worm 16. The spindle 14 has an opening 18 formed through it, and the left end of the opening is frusto-conical, as shown at 19.

Supported by the spindle 14 is an arbor 20. The right end of the arbor 20 is frusto-conical as indicated at 21, and is adapted to be received in the frusto-conical part 19 of the spindle 14. The right end of the arbor 20 is provided with a threaded cavity 22 into which the left end of a bolt 23 is threaded. The bolt 23 extends outward from the right end of the opening 18, and has a head 24 formed on the right end thereof, which head is adapted to engage the right end of the spindle 14. By screwing the bolt 23 into the cavity 22 the arbor 20 is secured to the spindle 14.

The part of the arbor extending from the spindle 14 is provided with a central cylindrical portion 28 and a reduced end 29. Between the portion 28 and the end 29 is an annular shoulder 30. Adapted to be placed on the reduced end 29 in engagement with the shoulder 30 is a primary centralizing-member 31. The primary centralizing-member 31 preferably has an external cylindrical face 32 and a cylindrical opening 33 through which the reduced end 29 is extended. Adapted to slide on the central portion 28 is a secondary centralizing-member 34. The secondary centralizing-member 34 has a frusto-conical face 35 which is directed toward the primary centralizing-member 31. A cylindrical opening 36 is formed through the secondary centralizing-member 34, through which the central part 28 of the arbor 20 extends.

Placed on the reduced end 29 of the arbor 20 is the primary-means of the invention, which consists of a washer 38 and a primary nut 39 which is threaded on primary threads 40, which primary threads 40 are formed on the reduced end 29. It should be noted that the primary threads 40 are left hand threads.

That portion of the arbor 20 adjacent to the right end of the central portion 28 is provided with secondary threads 42 which are right hand threads. Adapted to be carried by this portion of the arbor 20 is a secondary-means in the form of a secondary nut 43, which is threaded onto the secondary threads 42. The left end-face 44 of the secondary nut 43 is adapted to engage the right end-face 45 of the secondary centralizing-member 34. The right part of the secondary nut 43 is provided with an annular lip 47 so that the spindle 14 may be engaged when the secondary nut 43 is advanced to the right.

The self-centering arbor of the invention

is designed so that it may concentrically support devices such as automobile wheels which have different sized openings, or openings of different degrees of taper. In the drawing the numeral 50 represents an automobile wheel having a brake-drum 51 which it is desired to turn down on the drum-lathe illustrated, for the purpose of truing it. The wheel 50 has a hub 51^a provided with a concentric frusto-conical opening 52. The manner of supporting the wheel 50 on the arbor 20 will now be described.

All of the parts of the arbor are assembled with the exception of the washer 38 and the primary nut 39. The wheel 50 is placed on the arbor substantially as shown in Figs. 1 and 2. The washer 38 and the nut 39 are then placed on the reduced end 29, and the nut 39 is advanced to the right until the wall of the frusto-conical opening 52 is brought into engagement with the left edge of the cylindrical face 32 of the primary centralizing-member 31. When this occurs the left part of the hub 51^a is retained concentric to the arbor 20. At this time the secondary nut 43 is resting in a position indicated by dotted lines 53, and the secondary centralizing-member 34 is resting in a position indicated by dotted lines 54. As shown in Fig. 2, at this time only the left part of the hub 51^a is centralized, and the right part thereof is not.

The next step in the attachment of the wheel 50 to the arbor 20 is to advance the secondary nut 43 from the position indicated by dotted lines 53, into the full line position of Fig. 2. This causes the secondary centralizing-member 34 to slide to the left of the central portion 28 of the arbor 20, and to engage the right part of the hub 51^a at the end of the frusto-conical opening 52. This engagement of these parts causes the right part of the hub 51^a to be moved into concentric relation with the arbor 20. The wheel 50 is now secured to the arbor 20 and the drum-lathe is now set into operation in order that the brake-drum 51 may be worked upon. By providing the primary threads in the form of left hand threads, and the secondary threads in the form of right hand threads, the pressure of the cutting tool against the brake-drum 51 tends to more tightly secure the wheel 50 to the arbor 20.

It will be seen from the foregoing description that the essential operation in attaching the wheel to the arbor is first, to move the wheel 50 relative to the primary centralizing-member 31 in order to cause engagement between the wall of the frusto-conical opening 52 and the wall 32 of the primary centralizing-member 31; and then to move the secondary centralizing-member 34 toward the wheel 50 in order to cause the secondary centralizing-member 34 to engage the wheel at the end of the frusto-conical opening 52.

The invention is designed so that various

devices having different sizes and different tapers of openings may be accommodated. For example, if the left end of the frusto-conical opening 52 were smaller, the primary centralizing-member 31 would engage the wall of the frusto-conical opening 52 nearer to the vertical center of the wheel 50. If the left end of the opening 52 were larger, the primary centralizing-member 31 would engage it nearer the left end thereof. If the right end of the frusto-conical opening 52 were smaller it would engage a smaller part of the frusto-conical face 35 of the centralizing-member 34, and if the right end of the frusto-conical opening 52 were larger it would engage a larger part of the frusto-conical face 35.

The primary and secondary centralizing-members will concentrically support devices having different sizes of openings, and openings of different tapers. In addition to this the parts are designed so that larger or smaller centralizing-members may be readily substituted for those shown in the drawing.

25 When it is desired to remove the arbor 20 from the spindle 14, the bolt 23 is unscrewed and the secondary nut 43 is advanced to the right. This causes the lip 47 to engage the spindle 14, and causes the arbor 20 to be moved to the left relative to the spindle 14.

I claim as my invention:

1. In a self-centering arbor of the class described, the combination of: an arbor; a primary centralizing-member engaging a shoulder on said arbor, adapted to engage the device to be supported; primary-means for engaging and moving the device into engagement with said primary centralizing-member; a secondary centralizing-member carried by said arbor, and adapted to engage the device; and secondary-means for moving said secondary centralizing-member into engagement with the device.

2. In a self-centering arbor of the class described, the combination of: an arbor, a primary centralizing-member engaging a shoulder on said arbor, adapted to engage the interior of the device to be supported; primary-means for engaging and moving the device into engagement with said primary centralizing-member; a secondary centralizing-member carried by said arbor, and adapted to engage the device; and secondary-means for moving said secondary centralizing-member into engagement with the device.

3. In a self-centering arbor adapted to support a device having a frusto-conical opening, the combination of: an arbor; a primary centralizing-member on said arbor, adapted to rest in the frusto-conical opening; primary-means for engaging and moving the device relative to said primary centralizing-member to cause the wall of the frusto-conical opening to engage said primary centralizing-member; a secondary centralizing-member; and secondary-means for moving said secondary centralizing-member into engagement with the device.

ing-member on said arbor; and secondary-means for moving said secondary centralizing-member into engagement with the device.

4. In a self-centering arbor adapted to support a device having a frusto-conical opening, the combination of: an arbor; a primary centralizing-member on said arbor, adapted to rest in the frusto-conical opening; primary-means for engaging and moving the device relative to said primary centralizing-member to cause the wall of the frusto-conical opening to engage said primary centralizing-member; a secondary centralizing-member on said arbor, having a frusto-conical face adapted to engage the device at one end of the frusto-conical opening; and secondary-means for moving said secondary centralizing-member into engagement with the device.

5. In a self-centering arbor adapted to support a device having a frusto-conical opening, the combination of: an arbor; a primary centralizing-member on said arbor, adapted to rest in the frusto-conical opening; primary-means for engaging and moving the device relative to said primary centralizing-member to cause the wall of the frusto-conical opening to engage said primary centralizing-member; a secondary centralizing-member on said arbor; and secondary-means in the form of a nut threaded on said arbor for moving said secondary centralizing-member into engagement with the device.

6. In a self-centering arbor adapted to support a device having a frusto-conical opening, the combination of: an arbor; a primary centralizing-member on said arbor, adapted to rest in the frusto-conical opening; primary-means for engaging and moving the device relative to said primary centralizing-member to cause the wall of the frusto-conical opening to engage said primary centralizing-member; a secondary centralizing-member on said arbor, having a frusto-conical face adapted to engage the device at one end of the frusto-conical opening; and secondary-means in the form of a nut threaded on said arbor for moving said secondary centralizing-member into engagement with the device.

7. In a self-centering arbor adapted to support a device having a frusto-conical opening, the combination of: an arbor; a primary centralizing-member on said arbor, adapted to rest in the frusto-conical opening; primary-means in the form of a nut threaded on said arbor for engaging and moving the device relative to said primary centralizing-member to cause the wall of the frusto-conical opening to engage said primary centralizing-member; a secondary centralizing member on said arbor; and secondary-means for moving said secondary centralizing-member into engagement with the device.

8. In a self-centering arbor adapted to support a device having a frusto-conical opening, the combination of: an arbor; a primary centralizing-member on said arbor, adapted to rest in the frusto-conical opening; primary-means in the form of a nut threaded on said arbor for engaging and moving the device relative to said primary centralizing-member to cause the wall of the frusto-conical opening to engage said primary centralizing-member; a secondary centralizing-member on said arbor; and secondary-means in the form of a nut threaded on said arbor for moving said secondary centralizing-member into engagement with the device.
